SHOE

Samuel Goldberg, 33 Crooke Ave., Brooklyn, N.Y.

Filed July 20, 1964, Ser. No. 80,924

Term of patent 14 years

(Cl. D7—5)

The dominant features of the design reside in the portions shown in full lines.

I claim:

The ornamental design for a shoe, substantially as shown and described.
